Des. 236,071
Patented July 29, 1975

236,071

HOLDER FOR SCRUB PADS OR THE LIKE

Ronald O. Zemke, White Bear Lake, Minn.
(P.O. Box 33427, St. Paul, Minn. 55133)

Filed Jan. 18, 1974, Ser. No. 434,648

Term of patent 14 years

Int. Cl. D7—05; D4—01
U.S. Cl. D7—178

FIG. 1

FIG. 2

FIG. 3

FIG. 4

FIG. 1 is a plan view of a holder for scrub pads or the like embodying my design;

FIG. 2 is a front elevational view thereof, the rear elevational view being substantially a mirror image thereof;

FIG. 3 is a bottom view; and

FIG. 4 is a right end view, the left end being substantially a mirror image thereof.

I claim:

The ornamental design for a holder for scrub pads or the like, substantially as shown and described.
